SPOOL OR REEL

Application filed May 15, 1931. Serial No. 537,651.

This invention relates to improvement in spools or reels and particularly to such as are formed from sheet-metal and adapted to contain tape, wire, and various other materials.

5 These spools usually comprise a tubular core with disk-like ends applied thereto, and in some uses of these spools they are subjected to considerable strain, so that it is necessary to form them from comparatively heavy 10 material or to reinforce the parts. The object of this invention is to so construct the core and heads that they may be readily assembled and will withstand the strains imposed upon them, and the invention consists 15 in the construction as hereinafter described and particularly recited in the claim.

In the accompanying drawings:

Fig. 1 is a side view of a spool or reel constructed in accordance with my invention;

20 Fig. 2 is an end view of the same;

Fig. 3 is a face view of one of the ends detached;

Fig. 4 is a perspective view of the core detached;

25 Fig. 5 is a sectional view on the line 5—5 of Fig. 2;

Fig. 6 is a sectional view on the line 6—6 of Fig. 2;

30 Fig. 7 is a sectional view corresponding to Fig. 5, showing the tongues turned inward; and

Fig. 8 is a sectional view corresponding to Fig. 6, with the tongues turned inward.

In carrying out my invention, I form the 35 core 10 from a strip of sheet-metal rolled to form a tube, or the core may be drawn. The ends of the core will be provided with tongues 11, and preferably on each side of the tongues the end of the core is formed with notches 12.

40 The ends 13 are also formed from sheet-metal, and preferably the edges 14 are rolled to form a bead and to stiffen the ends. These ends are formed with central perforations 15 through which a mandrel may extend, and

45 preferably the inner edge 16 of these perforations will be turned inward. Equally spaced from the perforation and from each other, the ends are formed with slots 17 through which the tongues 11 may extend, and around these slots the metal is depressed,

forming recesses 18 of a depth corresponding to the thickness of the tongues 11 and into which recesses the tongues 11 are turned, and the edges of these depressions extend into the spaces formed by the notches 12, 55 so that the tongues 11, resting in the recesses 18, tend to prevent the ends turning on the tubular core, and the sides of the recess extending into the spaces formed by the notches 12, also hold the parts against turning one 60 upon the other. The tongues may be turned outward, as shown in Figs. 2 and 6; or inward, as shown in Figs. 7 and 8.

This construction not only provides a rigid 65 spool or reel, but also by forming the recesses into which the tongues extend, there are no projections beyond the surface of the ends, so that paper disks containing printed matter may be readily applied to the ends.

It is obvious, without illustration, that the 70 notches 12 may be omitted, as the tongues turning down into the recesses formed in the ends will prevent the ends from turning on the core and avoid shearing of the tongues.

I claim:

A spool or reel comprising a tubular core formed at its ends with projecting tongues and with notches on each side of the said tongues, and ends formed with slots through which the tongues extend and with recesses 80 around said tongues, said recesses forming projections adapted to enter the notches formed in the ends of the core.

In testimony whereof, I have signed this 85 specification.

OTTO A. BOESEL.
